(57) **CLAIM**

The ornamental design for a multi-tool, as shown and described.

DESCRIPTION

FIG. 1 is a perspective view of the multi-tool in accordance with the present invention, shown with environment; FIG. 2 is a top plan view thereof;

FIG. 3 is a bottom plan view thereof;

FIG. 4 is a left elevation view thereof;

FIG. 5 is a right elevation view thereof;

FIG. 6 is a front elevation view thereof;

FIG. 7 is a rear elevation view thereof;

FIG. 8 is a first perspective view of the multi-tool in accordance with the present invention, shown without environment;

FIG. 9 is a second perspective view thereof;

FIG. 10 is a top plan view thereof;

FIG. 11 is a bottom plan view thereof;

FIG. 12 is a left elevation view thereof;

FIG. 13 is a right elevation view thereof;

FIG. 14 is a front elevation view thereof; and,

FIG. 15 is a rear elevation view thereof.

The broken lines in the drawings depict portions of the multi-tool that form no part of the claimed design.

1 Claim, 9 Drawing Sheets
